[57] CLAIM

The ornamental design for a data jack for surface mounting assembly, as shown and described.

DESCRIPTION

FIG. 1 is a perspective view of my design for a data jack for surface mounting assembly;

FIG. 2 is a top plan view of my design for a data jack for surface mounting assembly;

FIG. 3 is an end elevational view of my design for a data jack for surface mounting assembly;

FIG. 4 is an elevational view of the end opposite that shown in FIG. 3 of my design for a data jack for surface mounting assembly;

FIG. 5 is a bottom plan view of my design for a data jack for surface mounting assembly;

FIG. 6 is a side elevational view of one side of my design for a data jack for surface mounting assembly; and,

FIG. 7 is a side elevational view of the opposite side of my design for a data jack for surface mounting assembly.
